UNITED STATES PATENT OFFICE.

GRANVILLE A. HUMASON, OF SHREVEPORT, LOUISIANA, ASSIGNEE OF ONE-THIRD TO
EDWARD B. BIERCE AND ONE-THIRD TO JOHN W. PARKER, BOTH OF HARRIS COUNTY,
TEXAS.

DRILL-BIT.

1,226,508.

Specification of Letters Patent. Patented Dec. 30, 1919.

Application filed March 18, 1918. Serial No. 233,317.

To all whom it may concern:

Be it known that I, GRANVILLE A. HUMASON, a citizen of the United States, residing at Shreveport, in the county of Caddo and State of Louisiana, have invented certain new and useful Improvements in Drill-Bits, of which the following is a specification.

This invention relates to new and useful improvements in a drill bit.

10 The object of the invention is to provide a bit of the character described which is especially adapted for deep well drilling by the rotary process.

In drilling by the rotary process, a drill 15 stem is used which is rotated by means of the well known rotary. To the lower end of this stem the bit is attached, usually by means of a drill shank, one end of which is threaded onto the lower end of the drill 20 stem and into the other end of which the shank of the bit is threaded. The bit, in use, must often be removed and replaced, as the same must often be sharpened, and furthermore said bit is subjected to great strain 25 in drilling through hard strata, so that the threads on the shank of the bit and the corresponding threads of the drill collar soon become battered and worn, so that the bit becomes loose and in withdrawing 30 the stem, the bit is liable to become separated therefrom, and drop into the bore, thus entirely preventing further drilling, or making the drilling very difficult.

It is the object of this invention to provide an improved form of the bit and shank whereby the bit may be securely attached to the drill stem, so that there will be no liability of the bit becoming loosened when the drill stem is rotated backwardly, or on 45 account of the wearing of the threads by means of which the bit is secured in said shank.

A further feature of the invention resides in the provision of a bit which may be 50 provided with a plurality of detachable blades securely held in place by means of said shank.

With the above and other objects in view, the invention has particular relation to 55 certain novel features of construction, arrangement of parts and use, an example of which is given in this specification and

illustrated in the accompanying drawings wherein:

Figure 1, is a side elevation of the bit 55 and shank shown partially in section.

Fig. 2, is a fragmentary side elevation of a modified form thereof.

Fig. 3, is a transverse sectional view taken on the line 3—3 of Fig. 2, and 60

Fig. 4, is a side elevation of one of the detachable blades employed.

Referring now more particularly to the drawings wherein like numerals of reference designate similar parts in each of the figures, the numeral 1 refers to a drill 65 stem, the lower end of which is threaded into the upper end of the drill shank 2. The lower end of this shank is enlarged, forming an abrupt annular shoulder 3, and 70 head 4. The head 4 is externally threaded to receive the sleeve 5. The upper end of this sleeve is cylindrical in shape, rounded off at the lower end, and is contracted to form an annular flange 6, 75 which receives the upper end of the drill shank 2, and rests upon the annular shoulder 3. The numeral 7, refers to an ordinary fish-tail blade which has the upper portion 8 exteriorly threaded for attachment 80 to the lower end of the sleeve 5, said sleeve projecting a sufficient distance downwardly from the head 4 for this purpose. The head 4 has a transverse mortise cut 85 therethrough, the upper part of which is enlarged, as at 10, forming an approximately key-hole shaped slot through the head. Integral with the shank of the blade and projecting upwardly therefrom is a tenon 11, 90 which fits snugly in said mortise, thus dovetailing the blade into the drill head. The tenon 11 thus receives the strain due to rotation and relieves the thread on the drill shank thereof. The ordinary fish-tail bit 95 is provided with only two blades, but additional blades, as 12, may be provided if desired. In case additional blades are provided, they are made detachable, and are fitted into vertical grooves 13, in opposite 100 sides of the shank 8, said blades being provided with tenons 14, shaped like tenons 11, previously described, and which are fitted into mortises 15, extending radially with reference to the mortise 9. The sleeve 5 fits

over the tenons 14, and locks the detachable blades 12 securely in place.

In attaching the blades to the drill head, the tenon 11 is brought into alignment with the mortise 9, and moved laterally until it is seated therein. The sleeve 5 is then fitted over the upper end of the drill shank and screwed down over the enlarged head 4, and the shank 8, of the blade, thus securing the 10 same in position and locking the tenon in the mortise. In case additional blades, as 12, are employed, before screwing down the sleeve 5, these blades are seated in the grooves 13, and the tenons 14 are seated in 15 the corresponding mortises 15 of the head 4, and the sleeve 5 is then screwed down over the shank 8, thus locking said detachable blades 12 securely in position.

In the modified form shown in Fig. 2 20 the upper portion of the head 4 and the corresponding portions of the tenons 14, as well as the opposite portion of the sleeve 5 are left blank. The head is in two sections fitting together along the transverse plane 25 indicated at 17, so that in case the tenons locking the blades to the head 4 should break, the head will be permitted to rotate, in the sleeve 5, but the flange 6 will lock the

bit against detachment from the stem so that there will be no possibility of the bit 30 becoming lost in the bore.

Water passageways 16, 16, are provided down through the shank 2, issuing from the lower end of the head through which water flows from the interior of the drill stem 35 to the cutting points so as to flush the bore and carry away the cuttings from the bit.

What I claim is:

In a rotary drill, a shank, an enlarged head on the lower end thereof, a mortise 40 therein, a shoulder on said enlarged head, a flat blade fitting in said mortise in said head, a sleeve fitting over said shank, and having a threaded connection with said blade, and an inwardly extending flange on said 45 sleeve-fitting over said shoulder whereby the blade is secured against detachment therefrom.

In testimony whereof I have signed my name to this specification in the presence of 50 subscribing witnesses.

GRANVILLE A. HUMASON.
